UNITED STATES PATENT OFFICE.

WILLIAM E. WOODARD, OF SCHENECTADY, NEW YORK.

TRUCK-BOLSTER.

1,100,275.

Specification of Letters Patent. Patented June 16, 1914.

Application filed March 13, 1914. Serial No. 824,375.

To all whom it may concern:

Be it known that I, WILLIAM E. WOODARD, of Schenectady, in the county of Schenectady and State of New York, have invented 5 a certain new and useful Improvement in Truck-Bolsters, of which improvement the following is a specification.

My invention relates to bolsters for the trucks of railroad rolling stock, and its object is to provide a swing or lateral motion bolster which shall embody the same characteristics, as to capacity of lateral motion and the exertion of proper resistance thereto, as are presented in bolsters supported on 15 swing links in the ordinary manner, with a reduction in the number of parts and the requirement of no greater space than is occupied by a bolster which is incapable of lateral motion.

20 The improvement claimed is hereinafter fully set forth.

In the accompanying drawings: Figure 1 is a vertical longitudinal central section through a truck bolster illustrating an application of my invention; Fig. 2, a plan or top view of the major portion of the same; Fig. 3, a transverse central section; Fig. 4, a partial longitudinal section, on an enlarged scale, on the line *a a* of Fig. 5, illustrating a structural modification; and, Fig. 5, a transverse section, on the line *b b* of Fig. 4.

It is well recognized in railroad practice 35 that it is decidedly desirable, and, under certain conditions, essential, that car trucks should be of such construction as to permit the center pins of the cars to be laterally deflected, to the end of easing blows on the road bed and rails in passing curves. In entering and leaving curves or striking uneven places in the track, the trucks are suddenly deflected laterally from their normal line of movement, which deflection transmits a blow or sudden pressure 40 to the center pin of the car, with the result that the latter is subjected to a sudden lateral shock, with a corresponding reaction on the track structure. Trucks provided 45 with bolsters capable of transverse lateral motion under these conditions, do not transmit the shock fully to the car body, as the deflection of the bolster materially lessens the shock, and the reaction upon the track is correspondingly reduced.

50 The correctness of principle of lateral motion trucks is, and has been for a long

time past, fully admitted by constructors and operators of railroad rolling stock, in passenger car design, and it is now embodied in the construction of practically all 55 trucks for this class of equipment. Attempts have also been made to provide a somewhat similar lateral motion in freight car and other trucks, by the interposition of rollers or sliding plates between the bolster 60 and the springs, so as to allow a certain amount of lateral motion to the bolster, relatively to the side frames of the truck. In such case, the characteristics of resistance to lateral motion are different from 65 those obtaining with the swinging links ordinarily applied in passenger car trucks, by reason of the mechanical limitations of the devices used.

My invention is designed to afford the 70 lateral motion and lateral resistance characteristics of the ordinary swing link bolster, under a construction involving the use of a less number of parts, and with a reduction in the space required for the lateral 75 movements of the bolster proper.

Referring to the drawings, in the practice of my invention, I provide an outer or main bolster, 1, which, as shown in Figs. 3 and 5, is of substantially U or channel section, 80 and on which, adjacent to its ends, there are formed lateral recesses, 1^a, adapted to fit the ordinary bolster guides of the side members of a truck frame, without the capacity of relative lateral motion, other than the 85 ordinary clearance therein. The ends of the main bolster, 1, are supported on the truck frame through the intermedium of spring arrangements of any suitable known form, which, as they do not form any part 90 of my present invention, are not herein shown.

An inner or supplemental bolster, 2, of substantially inverted U or channel section, 100 is located within the main bolster, 1, with the capacity of longitudinal movement relatively thereto, and, consequently, of lateral or transverse movement relatively to the truck frame. The supplemental bolster is supported, adjacent to its ends, upon the 105 main bolster, 1, by rockers, 3, having segmental lower journals, 3^a, resting in corresponding bearings, 1^b, extending transversely in the main bolster, and having curved upper faces, 3^b, abutting on bearing 110 faces, 2^b, on the lower side of the top plate of the supplemental bolster, 2. The

rockers, 3, permit the longitudinal movement of the supplemental bolster, relatively to the main bolster, while opposing the necessary resistance thereto, and by proper changes of the contour of the bearing surfaces of the rockers, or of the surfaces of the supplemental bolster which rest thereon, this resistance may be made an increasing, a constant, or a decreasing quantity, as fully set forth in Letters Patent of the United States No. 1,060,222, granted and issued to me under date of April 29, 1913. I consider it to be most desirable to provide a resistance which shall approximately correspond to that exerted in the case of a bolster supported on swinging links, as ordinarily applied in passenger car trucks.

The supplemental bolster, 2, may be supported so that in its movements, its upper surface will remain parallel with that of the main bolster, or the surfaces bearing on the rockers may, as shown, be disposed so as to cause the supplemental bolster to tilt or be inclined relatively to the main bolster, in its movements, as in the case of bolsters supported on swinging links.

Under normal conditions, the surfaces of the rockers and of the bearings of the supplemental bolster will remain in proper operative relation, but in order to prevent accidental displacement, the rockers may be coupled to the supplemental bolster by U shaped links, 4, which pass through openings in the top plate of the supplemental bolster, and are turned over at their ends thereon, said links passing under, but entirely clear of, lateral lugs 3^a, on the rockers. If the supplemental bolster should be accidentally lifted or displaced, the links, 4, will insure its return to proper relation with the rockers. The separation of the main and supplemental bolsters, in cases of accident or derailment, is prevented by a center pin, 5, which passes through a lower center plate, 2^a, on the supplemental bolster, and through a longitudinal slot, 1^a, in the bottom plate of the main bolster, the center pin being held in position by a nut, 5^a, and washer, 5^b, on its lower end. The center pin thereby prevents the withdrawal of the supplemental bolster from its position in the main bolster, while providing for its

range of longitudinal and vertical movement relatively thereto.

I claim as my invention and desire to secure by Letters Patent:

1. In a bolster structure for railroad car trucks, the combination of an outer or main bolster, an inner or supplemental bolster, and rockers journaled transversely in the main bolster and supporting the supplemental bolster.

2. In a bolster structure for railroad car trucks, the combination of an outer or main bolster having lateral recesses adjacent to its ends for engagement with bolster guides and transverse journal bearings, rockers journaled in said bearings and having curved upper surfaces, and an inner or supplemental bolster supported on said surfaces.

3. In a bolster structure for railroad car trucks, the combination of an outer or main bolster, an inner or supplemental bolster located therein, rockers journaled transversely in the main bolster and supporting the supplemental bolster, and links connected to the supplemental bolster and passing under lugs on the rockers.

4. In a bolster structure for railroad car trucks, the combination of an outer or main bolster, an inner or supplemental bolster located therein and having a center plate on its top, rockers journaled transversely in the main bolster and supporting the supplemental bolster, a center pin fitting in the center plate and in a longitudinal slot in the main bolster, and means for preventing vertical displacement of the center pin.

5. In a bolster structure for railroad car trucks, the combination of an open topped outer or main bolster having lateral bolster guide recesses adjacent to its ends and transverse journal bearings on its bottom, an inner or supplemental bolster of inverted U section located within the main bolster and having rocker bearing surfaces on the inner side of its top plate; and rockers journaled in the bearings of the main bolster and having curved upper surfaces abutting on the bearing surfaces of the supplemental bolster.

WILLIAM E. WOODARD.
